UNITED STATES PATENT OFFICE

138,298

DESIGN FOR AN ASH TRAY

Samuel L. Gerson, Bridgeton, N. J.

Application May 4, 1944, Serial No. 113,477

Term of patent 7 years

(Cl. D85—2)

To all whom it may concern:

Be it known that I, Samuel L. Gerson, a citizen of the United States, residing in Bridgeton, Cumberland County, New Jersey, have invented a new, original, and ornamental Design for an Ash Tray, of which the following is a specification, reference being had to the accompanying drawing, forming a part thereof.

Fig. 1 is a view in perspective of an ash tray showing my new design;

Fig. 2 is a plan view, and

Fig. 3 is a side elevational view of the tray.

I claim:

The ornamental design for an ash tray, as shown.

SAMUEL L. GERSON.
